LAPPING TOOL

Abraham Simons, Monsey, N. Y.

Application September 11, 1951, Serial No. 246,017

5 Claims. (Cl. 51—184.1)

1

My invention relates to a new and improved tool.

The invention is illustrated in connection with a lapping tool.

A tool of this type can be made and assembled at low cost, and it does very accurate work and automatically fixes the end of the respective lapping operation.

Other objects and features and advantages of my invention are set forth in the annexed description and drawings, which illustrate a preferred embodiment of the invention.

Fig. 1 is an axial longitudinal section, partially in elevation, showing the complete assembled tool, prior to the insertion of the lapping rods into the bore which is to be lapped.

Fig. 2 is an elevation of the lapping rods and their head. The lapping rods are shown as bent out of their initial straight shapes, into their normal selected bent shapes, in which said bent rods are yieldingly maintained by their resilient or springy properties.

Figs. 3 and 4 are respectively sections on the lines 3—3 and 4—4 of Fig. 1.

Fig. 5 is a transverse cross-section which shows the lapping rods in the bore of a wire-drawing die, at the end of a lapping operation.

The half-round rods 1 and 2 are made of steel or other suitable material. Said rods 1 and 2 have adjacent and lateral and planar faces 1a and 2a. When the planar faces 1a and 2a of the identical rods 1 and 2 are in contact, said rods 1 and 2 form a longitudinal cylinder which has the axis 9.

The head 3 has an outer helical thread 4, a front longitudinal bore 6 and a rear longitudinal polygonal recess 5.

The rods 1 and 2 have initial straight shapes. Said rods 1 and 2 are initially assembled with their lateral planar faces 1a and 2a in full contact along the entire lengths of the identical rods 1 and 2, up to their front end-walls 1b and 2b. The rear end-parts of said straight rods 1 and 2 are then inserted into bore 6 of head 3, in which said rear end-parts fit closely. Said fit may be a drive fit or any mechanical means may be used to fix said abutting rear end-parts to the longitudinal cylindrical wall of bore 6. At that time, the cylinder which is formed by the initial straight rods 1 and 2 has the same longitudinal axis 9 as bore 6 and recess 5.

The rods 1 and 2 are then bent transversely away from each other in front of head 3, to the normal selected bent shapes shown in Fig. 2, in order to form a tool-part T. The bent parts of

rods 1 and 2 are equally transversely inclined to the line 9. If said bent parts are moved towards each other or away from each other from their normal bent positions of Fig. 2, the resilience of said bent parts returns them automatically to their positions of Fig. 2.

This embodiment has a holder 7 which is operated by hand.

Said holder 7 has a rear end-wall 7a and a longitudinal bore 7c.

The rear end-part of bore 7c has a thread 8. The front end-part of bore 7c has a thread 8a.

The tip 10 has an axial longitudinal bore 10f. Said tip 10 has a rear extension 10a which has a thread 10d. Tip 10 also has an annular and planer shoulder 10c which is perpendicular to the common longitudinal axis of bore 7c and of the assembled head 3, and a front cylindrical limiting or gauge wall 10b.

Fig. 1 is substantially to scale. When assembled as shown, bores 10f and 7c have the same longitudinal axis, which is coincident with axis 9 and the common axis of bore 6 and recess 5.

In order to assemble the parts, the spread-apart bent rods 1 and 2 are bent transversely towards each other from their positions of Fig. 2, until the tips of said rods 1 and 2 can be inserted into bore 7c and pushed through holder 7. Head 3 is now turned to the stop position shown in Fig. 1 so that the interengaged threads 4 and 8 releasably fix head 3 to holder 7.

The rods 1 and 2, if released, separate transversely until their rounded outer surfaces engage the front end of bore 7c.

The front ends of rods 1 and 2 are temporarily held together, until tip 10 is slipped rearwardly upon said front ends. The rear extension 10a is now screwed into thread 8a, until planar transverse shoulder 10c abuts the planar transverse end-wall 7b of holder 7. The interengaged threads 8a and 10d releasably fix tip 10 in the position of Fig. 1.

Fig. 3 shows a transverse line which is the trace of a transverse axial plane which is perpendicular to the lateral faces 1a and 2a. The points 15a and 15b of this transverse line therefore designate the laterally outermost longitudinal lines of the rounded or semi-cylindrical outer surfaces of rods 1 and 2.

In the assembled tool of Fig. 1, said rounded surfaces of rods 1 and 2 abut the longitudinal cylindrical limit wall 10b of tip 10. Said limit wall 10b is coaxial with bores 10f, 7c, 6 and recess 5. There is then a selected transverse distance 55 between the planar faces 1a and 2a, and another

selected transverse distance between the longitudinal lines which are represented by points 15a and 15b.

A wire-drawing die B or other article has a bore 16 which is to be lapped. Said bore 16 has circular cross-sectional lines, one of which is shown in Fig. 5.

The original diameter of bore 16, or of the part of bore 16 which is to be lapped, is less than the diameter of the cylindrical limiting wall 10b.

The front operating end-portions of rods 1 and 2, which are located in front of the tip 10, are therefore forced transversely towards each other, in order to insert said front operating end-portions into bore 16, at the start of the respective lapping operation. At said start, there are equal clearances between the rounded surfaces of rods 1 and 2 and limiting wall 10b.

As the lapping continues, bore 16 is enlarged until rods 1 and 2 abut limiting wall 10b, thus automatically stopping further enlargement of bore 16. The wall 10b thus acts as an automatic gauge.

The tip 10 may be replaced by another tip, which has a limiting or gauge wall 10b of different diameter than the initial wall 10b.

I have described a preferred embodiment of my invention, but numerous changes and omissions and additions and substitutions can be made without departing from the scope. The invention also includes the subcombinations and parts of the complete tool.

Thus, the rods 1 and 2, instead of being halves of a cylinder, can be halves of a frusto-cone, in which the frusto-conical shape may be of greater diameter at its rear end than at its front end. In such case, the rods 1 and 2 can be longitudinally adjusted relative to holder 7 and tip 10, so that the transverse spacing between the front-end portion of rods 1 and 2 can be adjusted as desired. In such case, the wall 10b can be either cylindrical or of any polygonal shape, or it may be frusto-conical. The important feature is to have only a line contact or point contact between the wall 10b and the rounded portions of rods 1 and 2.

I claim:

1. A lapping tool which comprises a hollow holder which has a longitudinal holder-bore and a front end and a rear end, a hollow tip which has a longitudinal tip-bore which is aligned with said holder-bore, a plurality of lapping members which extend through said holder-bore and said tip-bore and which also extend forwardly of said tip, said lapping members being fixed to said holder in said holder-bore rearwardly of the front end of said holder-bore, said tip having a longitudinal gauge-wall, said lapping members being yieldingly biased transversely away from each other against said gauge-wall, said lapping members being movable towards each other away from said gauge wall.

2. A lapping tool according to claim 1 in which said lapping members are bendable and resilient and are thus biased by their resilience.

3. A lapping tool according to claim 1 in which there are two substantially identical half-cylindrical lapping members which have lateral planar faces, said lapping members being bent out of normal straight and abutting shapes to normal transversely divergent shapes, said lapping members being bendable and resilient and being biased towards said normal divergent shapes by their resilience.

10 4. A lapping tool which has a longitudinal axis, said tool comprising a plurality of longitudinally disposed lapping members which are flexible and resilient in a direction transverse to said longitudinal axis, said lapping members having original straight shapes, said lapping members having operating front end-portions and non-operating and holding rear end-portions, holding-means which hold said rear end-portions in fixed relation to each other, said front end-portions being bent out of their original straight shapes to normal bent shapes, said front end-portions diverging transversely from each other in a normal angle of divergence in said normal bent shapes and being biased by their resilience to yieldingly maintain said front end-portions in said normal bent shapes, and supplemental means which hold front end-portions in divergent relation and with an intermediate angle of divergence which is less than said normal angle of divergence.

20 5. A lapping tool which has a longitudinal axis, said tool comprising a plurality of longitudinally disposed lapping members which are flexible and resilient in a direction transverse to said longitudinal axis, said lapping members having original straight shapes, said lapping members having operating front end-portions and non-operating and holding rear end-portions, holding-means which hold said rear end-portions in fixed relation to each other, said front end-portions being bent out of their original straight shapes to normal bent shapes, said front end-portions diverging transversely from each other in a normal angle of divergence in said normal bent shapes and being biased by their resilience to yieldingly maintain said front end-portions in said normal bent shapes, and supplemental means which hold front end-portions in divergent relation and with an intermediate angle of divergence which is less than said normal angle of divergence, each said front end-portion being permanently bent transversely away from said axis relative to the respective rear end-portion.
